United States Patent Office.

THOMAS SHAPARD, OF HAYWOOD COUNTY, TENNESSEE.

Letters Patent No. 72,691, dated December 24, 1867.

IMPROVEMENT IN CLEANING COTTON.

The Schedule referred to in these Letters Patent and making part of the same.

TO ALL WHOM IT MAY CONCERN:

Be it known that I, THOMAS SHAPARD, of Haywood county, in the State of Tennessee, have invented a new and useful Machine for Cleaning Cotton of dust after it has gone from the gin; by the use of my ventilated lint-room or cotton-cleaner; and I do hereby declare that the following is a full, clear, and exact description of the construction and operation of the same, reference being had to the annexed drawing, making a part of this specification, in which—

Figure 1 shows the floor of the lint-room, and

Figure 2 shows the side of the lint-room, the opposite side being the same, except the door B (not in the opposite side.)

Figure 3 shows the end of the lint-room next to the gin.

C represents the flue of the gin, where the cotton goes from the gin to the lint-room. The opposite end of the lint-room is like fig. 3, except there is no opening, C, in the opposite end. The part of figure or drawing No. 1, marked A, shows the floor of a room, into which the cotton is thrown from the ventilated lint-room, through the door B, into a side room, of which C, in fig. 3, shows the end. Figs. 2 and 3 show that the lint-room is smaller at the bottom than the house, to allow the dust to escape entirely from the cotton. The floor of the lint-room (fig. 1,) is elevated, for the same purpose, some two feet above the floor of the house, if it has a floor. In the ordinary process, the cotton and dirt (after having been separated by the saw and brush,) go together into the close lint-room, where the cotton takes up the most of the dirt again, and in that condition is baled. By my cotton-cleaner, open spaces about three-fourths of an inch wide, are left in the bottom, sides, and ends of the room, being made of slats with the open spaces between them. The cotton-cleaner is protected from the weather by the house in which it is built. The slats, on the sides and ends, are attached, at the top, to the wall of the room or house, while at the floor, the spaces between the wall of the house and the slats or lint-room are about two feet, as shown in figs. 2 and 3. The wall of the house being perpendicular, the slats form the ventilated lint-room, which is, therefore, at the floor, about two feet smaller on each side and end than at the top. Under the influence of the current of air produced by the brush, the dirt is driven through these open spaces, and the person in the lint-room is able to throw the cotton through the door B, clear of dirt, and thus the value of the cotton is increased twenty-per cent. The house in which my cotton-cleaner or ventilated lint-room is built, I do not include in my claim for a patent.

What I claim as my invention, and desire to secure by Letters Patent, is—

The lint-room, as above described, made of slats, allowing the dust and dirt to escape, in lieu of the ordinary close lint-room, which does not allow the dust and dirt to escape.

THOS. SHAPARD.
